UNITED STATES PATENT OFFICE.

FRANK G. STERLING, OF LYNN, MASSACHUSETTS.

DESIGN FOR A PUZZLE BOX OR CASE.

SPECIFICATION forming part of Design No. 29,575, dated November 1, 1898.

Application filed October 6, 1898. Serial No. 892,866. Term of patent 3½ years.

To all whom it may concern:

Be it known that I, FRANK G. STERLING, of Lynn, in the county of Essex and State of Massachusetts, have invented and produced 5 a new and original Design for a Puzzle Box or Case, of which the following is a description.

The accompanying drawings are to be referred to and form a part of this specification.

10 Of the drawings, Figure 1 is a plan view of a puzzle box or case showing my new design. Fig. 2 is a cross-sectional view of the same, taken on the line 2 2 of Fig. 1.

The leading feature of my design consists, 15 as shown in the drawings, of two rows of hemispherical recesses *a a'*, formed in the bottom *b* of the box, the surface of which bottom is otherwise smooth and level. The said bottom surface is ornamented with a line *c*,

extending centrally between the said rows of 20 recesses, and on each side of the said line the bottom is further ornamented by the representation of a flag, one flag contrasting in design from the other.

Having fully described and disclosed my 25 invention, I declare that what I claim as new and of my invention and production is—

The design for a puzzle box or case as herein shown and described.

In testimony whereof I have signed my 30 name to this specification, in the presence of two subscribing witnesses, this 26th day of September, A. D. 1898.

FRANK G. STERLING.
